UNITED STATES PATENT OFFICE.

WALTER MONTGOMERY, OF CHICAGO, ILLINOIS.

CIGAR AND CIGARETTE HOLDER.

Application filed May 5, 1920. Serial No. 379,192.

To all whom it may concern:

Be it known that I, WALTER MONTGOMERY, a citizen of the United States, residing at Chicago, in the county of Cook and State of Illinois, have invented a new and useful Cigar and Cigarette Holder, of which the following is a specification.

The device forming the subject matter of this application is a cigar and cigarette holder, and one object of the invention is to provide novel means whereby the device may be caused to grip a cigar or cigarette readily.

Another object of the invention is to provide novel means whereby the saliva will be held back and be prevented from running down into the holder.

In the accompanying drawings:—

Figure 1 shows in side elevation, a device constructed in accordance with the invention; Figure 2 is a cross section on the line 2—2 of Figure 1; and Figure 3 is a longitudinal section.

The device forming the subject matter of this application comprises a body 1 which is split as at 2, to form resilient trough-shaped jaws 3. The mouth piece end of the body 1 preferably is closed as at 4, and has a reduced opening 5, the construction being such that the saliva cannot find its way from the mouth of the user into the body 1.

About the jaws 1 extends a tightening device in the form of a ring, the constituent members 7 and 8 of which are pivotally connected as shown at 9. The member 8 of

the tightening device has a recess 10 wherein is received the reduced end 16 of the member 7 of the tightening device, a set screw 11 or fastening element being threaded into the ends of the members 7 and 8 to prevent the ring 6 from opening.

When the ring 6 is slid forwardly along the jaws 3, the jaws will be compressed on the cigar or cigarette, and by advancing the screw 11 until the screw bears against one of the jaws 3, the ring or tightening device 6 may be held in any position to which it may have been adjusted longitudinally of the jaws 3. When the screw 11 is removed, the members 7 and 8 of the ring 6 may be opened, to permit the ring to be placed readily around the body 1 of the holder.

I claim:—

A device of the class described, comprising a body provided with resilient jaws; a ring slidable along the jaws and including pivotally connected members; and a tightening element engaging said members to hold them together, the tightening element cooperating with one of the jaws to hold the ring in adjusted positions longitudinally of the jaws.

In testimony that I claim the foregoing as my own, I have hereto affixed my signature in the presence of two witnesses.

WALTER MONTGOMERY.

Witnesses:

E. D. COHEN,
E. M. COSTELLA.
